UNITED STATES PATENT OFFICE

97,001

DESIGN FOR A SHUFFLE-BOARD GAME DEVICE

Theophile Reichard, Alameda, Calif.

Application October 30, 1934, Serial No. 53,819

Term of patent 7 years

To all whom it may concern:

Be it known that I, Theophile Reichard, a citizen of the United States, residing at Alameda, in the county of Alameda and State of California, have invented a new, original, and ornamental Design for a Shuffle-Board Game Device, of which the following is a specification, reference being had to the accompanying drawing, forming part thereof, in which

I claim:

The ornamental design for a shuffle-board game device, as shown.

THEOPHILE REICHARD.
